INTEGUMENT TREATING APPARATUS

Charles Nessler, Palisades, N. Y.

Application October 11, 1940, Serial No. 360,742

7 Claims. (Cl. 128—55)

This invention relates to apparatus for removing waste material from the surface of integuments, and is adapted for the treatment not only of the hands, face, arms, legs and other parts of the human body but also for the treatment of the hair and scalp, and of the fur of domestic animals.

In my application Ser. No. 120,860, filed January 16, 1937, now Patent No. 2,224,880, there is described an apparatus and method for activating, cleaning and stimulating the outer layers of skin and the underlying tissue by subjecting the skin surface to the rapid action of tapping and scratching elements and simultaneously directing a cooling current of air over the surface of the skin being treated.

The apparatus described in this application is designed to accomplish this object as well as other objects, including the removal of surplus hair, in a particularly efficient and practical manner.

It is well recognized that the normal function of the human skin is to give off various waste materials through the pores, and that unless this waste material, dead skin, dirt accumulations, etc., is properly removed from the outer surface of the skin, this natural function is impaired. In addition to the use of soap and water, toweling and various cleansing creams, numerous stimulating massage treatments have been proposed but these all fall short of accomplishing a thorough removal of waste material. Rubbing with a towel or massaging is accompanied by frictional generation of heat which attracts the blood to the skin surface and, therefore, the length of time of the rubbing or massage is very limited because the skin surface soon becomes very sensitive.

It is an object of this invention to provide improved apparatus for applying to the skin surface a combination of a frictional action by means of elements that produce a rapid tapping and scratching on the surface, and a cooling effect on the surface of the skin to avoid the attraction of blood to the skin surface.

One embodiment of my invention is illustrated in the accompanying drawings, in which

Figure 1 is a longitudinal sectional view of the apparatus taken on the line 1—1 of Fig. 2.

Figure 2 is a vertical sectional view of the apparatus taken on the line 2—2 of Fig. 1.

Figure 3 is a perspective view of a set of bristles that may be used in the apparatus.

Figures 4, 5 and 6 are perspective views of different types of pads that may be employed, and

Figure 7 is a sectional view of a portion of the machine shown in the lower portion of Fig. 1 but illustrating a modified construction thereof.

The apparatus illustrated comprises a fixed solid disc-shaped member 10 having a central opening 11 in which a bearing and shaft housing member 12 is fixed by means of a number of rivets or bolts 13. Within the bearing housing 12, a ball bearing race 14 is held in place, as by means of a press fit, to support within it a rotatable shaft 15. Nut 15a on the end of shaft 15 holds the shaft against axial movement relative to the bearing race 14. Fixed on a central portion of the shaft 15 is a rotor 16 made up of a hub 17 and spokes 18 that connect the hub to a solid cylindrical section 19.

Rotor 16 is preferably constructed with a number of slots 20 formed in the cylindrical portion 19 and having enlarged inner portions 21 to receive the bases of various types of pads or other friction elements that may be used in the apparatus. One or more elongated slots 22 may also be provided to receive the bristle pad elements 23 or the like.

Surrounding the other end of shaft 15 is another bearing housing member 24 fixed to a second ball bearing race 25, as by means of a press fit. Nut 25a on the end of shaft 15 may be used to prevent axial movement between the shaft and the bearing race 25. A second disc-shaped member 26 of a shape and size complementary to the disc member 10 may be attached by means of the rivets 27 to the flange of an elongated hollow handle 28. This assembly is designed to slip over the end of the bearing housing 24 and may be removably secured in place by means of the set screw 29 engaging the groove 30 in the bearing housing 24. The ball bearing races 14 and 25 and the shaft 15 are preferably constructed and arranged to permit free rotation of shaft 15 while preventing relative axial movement between the shaft 15 and the races 14, 25 and housings 12, 24.

To hold the two disc members 10 and 26 against rotation relative to each other, although this is not essential, I may provide a strap 31 of spring steel or the like secured at one end to the disc 10 by means of the rivet 32, and the other end of which snaps into a slot or groove 33 in the inner surface near the outer edge of the disc member 26 when this slot is rotated into the proper position. The disc members 10 and 26 may be provided with inwardly extending flanges 34 and 35 spaced just a slight distance from the outer surface of the edges of the rotor 16. The

outer edges of the disc members 10 and 26 preferably extend a substantial distance radially beyond the outer surface of rotor 16 and may be provided with two tubular rubber guards 36 and 37 seated in the grooves 38, 39 and extending around the outer edges of the discs 10 and 26.

Alternatively, as illustrated in Figure 7, the outer edges of the disc members 10 and 26 may be formed with integral solid beads 40, 41 thereon instead of the rubber guards 36 and 37.

The nut 15a preferably has at one end a slot 42 to receive the flat end of a flexible shaft 43 carried in the cable 44. This flexible shaft may be driven from any suitable source of power (not shown) such as an electric motor.

The discs 10 and 26, rotor 16 and the handle 28 may conveniently be made of any suitable plastic such as molded "Bakelite," while the bearing housings, shaft 15, ball bearing races and similar parts are preferably constructed of metal.

In the operation of this device, various types of friction elements may be employed. For example, for treating a person's arms, legs, hands, neck and face a double loop pad 45 (illustrated in Fig. 2) made up of a number of layers of soft cloth such as cheesecloth or other suitable material may be employed. This pad 45 is preferably composed of a plurality of strips of such cloth of approximately the width of the rotor 16. One end of these strips is secured around a core 46, the central portion of these strips is looped about another core member 47, while the other end of the strips is wrapped around the core member 48. These three core members are slipped into the three slots 20, 21, as illustrated in Fig. 2, and the disc 26 and handle 28, which had been previously removed for this purpose, are then slid over the end of the bearing housing 24 and secured in place by tightening the set screw 29.

The rotor 16 is now started, being driven by the flexible shaft 43 from any suitable source of power, and caused to rotate at a fairly high rate of speed. For example, a suitable speed for the rotor when the disc members 10 and 26 are approximately 5" in diameter would be 1,200 R. P. M. Obviously, with a larger diameter of apparatus, the R. P. M. of the rotor 16 may be reduced while with a smaller diameter apparatus, the speed may be increased. Furthermore, the speed given above is simply illustrative and is not critical, provided a sufficient speed is obtained to create a cooling current of air, as will be described.

The loops of cloth or other material of the friction element 45 between the cores 46, 47 and 47, 48 extend outwardly from the rotor surface due to centrifugal force, and the outer edges of these loops preferably extend a short distance radially beyond the outer edges of the rubber guards 36, 37, or of the beads 40, 41, as the case may be.

The apparatus is now held against the skin surface to be treated and the edges of the loops of cloth successively come into frictional contact with the skin, exerting a tapping and frictional or scratching action thereon in rapid succession. Simultaneously, a cooling current of air is caused to flow over the surface of the skin being treated due to the rapid rotation of the semi-solid elements of the pad 45. This cooling action drives blood away from the skin surface being treated and permits a long and vigorous treatment, removing waste material from the skin surface without the development of frictional heat or pain.

Other suitable friction elements may be employed. For example, in the treatment of the hair and scalp, it is desirable to provide one or more friction elements that are more substantial and have a harsher effect than a simple pad of cloth or paper. For this purpose, the bristle element 23, consisting of a plurality of flexible bristles 49 set in a soft rubber or other suitable base member 50, may be used either alone or with one or more of the pads shown in Figs. 4 and 5. This pad may be placed in the slot 22 after removal of the disc 26 and handle 28 as described above. After replacement of the disc 26 and handle 28, the rotor 16 may be started and the apparatus held against the scalp to be treated. When used with one or more pads, the action of the bristles augments the frictional and cooling action of the relative solid pad element and produces a more vigorous action on the hair and scalp.

Other suitable pads made of paper or similar materials may be used in place of the pad 45. For example, the pad illustrated in Fig. 4 consists of a number of sheets of soft paper 51 bound together at one edge to form a rib 52 for insertion in one of the slots 21. Free edges of this paper pad may be serrated as at 53. As this pad becomes soiled or worn, one or more of the sheets of paper can be readily torn off, exposing a fresh frictional surface. A similar pad is illustrated in Fig. 5, in which a number of sheets of paper are bound together at one edge to form a rib 55. The outer edges of these sheets of paper are left plain, but may be slit, as shown at 56, to produce a more flexible action on the skin surface being treated.

Still another form of pad that may be used to good advantage for the removal of superfluous hair is the pad illustrated in Fig. 6, which is similar to the pad shown in Fig. 4 except that the outer sheet is a sheet of emery paper 57 or similar abrasive material, and this abrasive paper together with the other sheets of softer paper are slit for a substantial distance, as shown at 58. It has been found that fine grades of emery paper and the like may be employed in this pad in accordance with my invention to remove quickly and painlessly superfluous hair from the arms and legs. Due to the concentrated cooling action of the pads on the surface of the skin being treated, this strong abrasive action on the skin does not produce any undue discomfort.

The friction elements employed according to my invention strike within a given area of skin being treated so rapidly as to give the impression of a continuously moving contact over a small area. This contact is a combination of tapping or light beating against the skin and a scratching action as the elements are drawn across the surface of the skin. Such a frictional contact generates heat but the heat is rapidly dissipated by the cooling current of air created by the pads or other means and caused to flow over the skin surface during the tapping and scratching. The net result, therefore, is the removal of waste material from the skin surface, which the air current helps to carry away, and a sensation of coolness of the skin surface during the treatment. A slight sense of warmth may be experienced after the treatment due to a reaction from the stimulation of the skin surface and cooling effect of the apparatus, but the treatment may be continued on a given surface of skin for many minutes without causing any discomfort or pain during or after the treatment. Treatments, even of

the normally sensitive areas of a person's skin, may thus be given which in a relatively few minutes produce the equivalent in stimulation and cleansing of an hour of vigorous rubbing with a towel. Repeated daily treatment of the backs of the hands and of the face have produced a surprising rejuvenation of the skin, by tightening the skin and thus reducing wrinkles.

Various modifications of the apparatus illustrated in the drawings are possible without departing from the principles of my invention. The proportions, sizes and shapes of the various parts may be varied. Handle 28 may be eliminated, if desired, provided some other convenient means is used for holding the apparatus. Also, the connecting strap 31 is not essential although it holds the discs 10 and 26 against relative rotation, offers a means for hanging the apparatus from a stand or other support, and provides a holder for a recorder card to catch for examination waste material removed from the skin or scalp, as described in my application Ser. No. 120,860. Also, the discs 10 and 26, and the rotor 16 do not have to be solid and imperforate. The imperforate side walls of discs 10 and 26 extending beyond the outer surface of rotor 16 are preferred, however, because they are believed to cooperate with the rotor and pads to produce a more efficient cooling effect on the integument.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. Apparatus for removing waste material from the surface of the skin comprising a rotor, a friction element mounted on the rotor for producing a scratching and tapping action and a cooling current of air on the skin, a pair of guard members on each side of said rotor having substantially imperforate portions extending radially beyond the surface of the rotor but not beyond the end of said friction element for confining said cooling current of air, means for rotating said rotor, and means for holding said guard members to prevent rotation thereof relative to each other.

2. Apparatus for removing waste material from the surface of the skin comprising a rotor, a friction element of sheet material having an abrasive surface mounted on said rotor for movement in

a direction substantially normal to its plane to create a cooling current of air on the skin, guard members on each side of said rotor having substantially imperforate portions extending radially beyond said rotor but not beyond the outer edge of said friction element for confining said cooling current of air, and means for rotating said rotor.

3. Apparatus for removing waste material from the surface of an integument comprising a shaft, a rotor carrying a friction element fixed to said shaft, bearing members on said shaft on each side of said rotor, a guard member for said rotor fixed to one of said bearing members, a guard member removably attached to the other of said bearing members, means extending between said guard members to prevent relative rotation thereof, and means for rotating said shaft.

4. Apparatus for removing waste material from the surface of an integument comprising a shaft, a rotor carrying a friction element fixed to said shaft, bearing members on said shaft on each side of said rotor, a guard member fixed to one of said bearing members, a second guard member removably attached to the other of said bearing members, and means for rotating said shaft.

5. Apparatus as defined in claim 4 in which the guard members are disc-shaped and have substantially imperforate portions extending radially beyond the rotor but not beyond the outer edge of the friction element thereon.

6. Apparatus for removing waste material from the surface of an integument comprising a shaft, a rotor carrying a friction element fixed to said shaft, bearing members on said shaft on each side of said rotor, a guard member fixed to one of said bearing members, a second guard member removably attached to the other of said bearing members, means attached to the first of said guard members for engaging said second guard member to prevent rotation thereof when attached to the other of said bearing members, and means for rotating said shaft.

7. Apparatus for removing waste material from the surface of the skin comprising a rotor mounted upon a shaft, a friction element carried by said rotor, disc-shaped guard members supported by said shaft on each side of the rotor and extending radially beyond the outer surface of the rotor, flanges extending from the sides of said guard members to cover the edges of said rotor, and means for rotating said shaft and rotor independently of said guard members.

CHARLES NESSLER.
